(57) **CLAIM**

The ornamental design for a control panel module substantially as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, right side and top perspective view of a control panel module comprising a new, original and ornamental design;

FIG. 2 is a front view thereof;

FIG. 3 is a back view thereof;

FIG. 4 is a top view thereof;

FIG. 5 is a bottom view thereof;

FIG. 6 is a left view thereof;

FIG. 7 is a right view thereof;

FIG. 8 is a front view of the control panel module of FIG. 1 having an element shown in color yellow;

FIG. 9 is a front view of the control panel module of FIG. 1 having an element shown in color white; and,

FIG. 10 is a front view of the control panel module of FIG. 1 having an element shown in color red.

The broken lines illustrate portions of the control panel module and form no part of the claimed design.
